SHUTTLE BOX SUPPORT FOR REPLENISHING LOOMS

Filed April 2, 1942

FIG. 2

UNITED STATES PATENT OFFICE

2,300,200

SHUTTLE BOX SUPPORT FOR WEFT REPLENISHING LOOMS

Benjamin W. Brouwer, Auburn, Mass., assignor to
Crompton & Knowles Loom Works, Worcester,
Mass., a corporation of Massachusetts

Application April 2, 1942, Serial No. 437,421

9 Claims. (Cl. 139—182)

This invention relates to improvements in weft replenishing mechanisms employing shifting shuttle boxes and it is the general object of the invention to provide means to hold the shuttle boxes in fixed position on the lay at those times in the cycle of loom operations in which replenishment can occur.

A type of pick and pick weft replenishing loom which recently has gone into use employs shifting shuttle boxes at the replenishing end of the loom and operates to renew the weft of the shuttle in the top box when the latter is in raised position. In such a loom it is customary to shift the shuttle boxes by a yieldable actuator for the purpose of preventing shuttle breakage should the shuttle fail to be completely boxed, but the yieldable actuator is likely to cause vibration of the shuttle boxes during the replenishing operation. The boxes each have shuttle binders and the sequence of shuttle motion is such that the lower box is empty when the upper box is being replenished and the binder for the lower box is therefore in shuttle checking position. It is an important object of my invention to provide an auxiliary support moving with the shuttle boxes and controlled by the binder of the lower box to afford additional support for the boxes when replenishment occurs.

In my prior Patent No. 2,263,261 I have shown a bobbin chute secured to the lower side of a set of shifting shuttle boxes together with a connection to the yieldable actuator so arranged that the actuating force for the boxes is transmitted through the bobbin chute. It is a further object of my present invention to mount an auxiliary support on the bobbin chute and control the same by the binder of the lower box in such a way as to support the chute and boxes when the lower box is empty, a condition which exists at replenishment. By such an arrangement the auxiliary support is always aligned with the binder of the lower box and rises and falls as the boxes shift without having interfering contact with any other part of the shuttle boxes.

It is a more particular object of my present invention to provide a lock lever pivoted to the bobbin chute and having the lower end thereof positioned to overhang a part of the lay when the lower shuttle box is empty. When a shuttle enters the lower box subsequent to replenishment the lever will be swung on its pivot to a position out of alignment with the lay to permit descent of the boxes.

With these and other objects in view which will appear as the description proceeds, my invention

resides in the combination and arrangement of parts hereinafter described and set forth.

In the accompanying drawing, wherein a convenient embodiment of my invention is set forth, Fig. 1 is a diagrammatic front elevation of the replenishing end of a pick and pick loom having my invention applied thereto,

Fig. 2 is an enlarged front elevation of a portion of Fig. 1, showing the shifting shuttle boxes in raised position with my invention in locking position,

Fig. 3 is a vertical section on line 3—3 of Fig. 2,

Fig. 4 is a view similar to Fig. 3 but with the parts in a different position, and

Fig. 5 is a detail horizontal section on an enlarged scale taken on line 5—5 of Fig. 2.

Referring particularly to Fig. 1, I have shown a loom frame 10 and lay 11 which swings back and forth on a rocker shaft 12. A rocker foot 13 secured to shaft 12 has slidably mounted therein a sleeve 14 attached at its lower end to a connector 15 which extends upwardly over a sheave 16 rotatably mounted on the lay. From the sheave the chain moves to well-known operating mechanism, such as a Knowles head not shown, which pulls on and releases a chain 17 forming part of connector 15 to raise and lower the sleeve. A box rod 20 extending through the sleeve 14 has the lower end thereof provided with a collar 21 for engagement with the bottom of the sleeve. The rod extends upwardly from the sleeve and is attached as at 22 to a bobbin chute 23. A spring 24 surrounding the box lifter rod is located between the top of sleeve 14 and the bobbin chute. When the connector 15 raises the sleeve 14 an upward force is transmitted through the spring 24 to the bobbin chute, and under ordinary conditions the spring is sufficiently strong to raise the boxes. If, however, a shuttle should fail to be completely boxed and should project into the path of some part carried by the lay, the spring 24 will be compressed to prevent breakage of the shuttle as the sleeve rises.

The shuttle box gang G comprises upper and lower shuttle boxes 30 and 31, respectively, which may be made as indicated in Figs. 2 and 3 with a box back 32 having depending lugs 33 which are secured as at 34 to lugs 35 on the bobbin chute. The upper box 30 has a horizontal top 35 secured to the back 32 while the lower box has a floor 36 also secured to the back 32. An intermediate shelf or floor 37 secured to and extending forwardly from the back 32 provides the floor for the top box and the top for the bottom box. The lay end 38 secured to the lay has inner and

outer box guides 40 and 41 to guide the gang G as it moves vertically with respect to the lay.

The loom is provided with weft replenishing mechanism a portion of which is indicated in Figs. 2 and 3. This mechanism comprises a frame 45 secured to the loom frame in front of the shuttle boxes and carrying a stud 46 on which the transerrer arm 47 is pivoted. A dog or latch 48 is pivoted to the transerrer arm at 49 and is normally in down position but can be raised by a connector 50 to transfer position when a replenishing operation of the loom is to occur. A reserve bobbin B will be under the transerrer arm at the time of transfer to be moved downwardly into shuttle S in the upper shuttle box when the latter is raised. At the time of replenishment the depleted bobbin from the shuttle S will move downwardly through the temporarily empty shuttle box 31 and between the right and left hand flanges 52 and 53, respectively, of the bobbin chute toward a bobbin can not shown.

The matter thus far described of itself forms no part of my present invention and may be made and operated as set forth in my previously mentioned patent.

In carrying my present invention into effect I cast a laterally extending boss 60 on the left hand flange of the bobbin chute and secure thereto a stud 61. A lever 62 is pivoted on the stud and has an upwardly extending arm terminating in a rearwardly projecting nose 63 positioned for engagement with the binder 64 of the lower box 31. A torsion spring 65 surrounds the hub 66 of lever 62 and is fastened at one end to the lever and at the other end to the boss 60. The effect of spring 65 is to tend to turn the lever 62 in a clockwise direction as viewed in Figs. 3 and 4 and hold the nose 63 in rear position, preferably against the binder 64.

The lay end 38 has secured to the under side thereof of a member 70 formed with a forward abutment 71 positioned for engagement with the lower arm 72 of lever 62. The member has an opening 73 behind the abutment proportioned to receive the arm 72 when the latter is in rear position as the boxes descend.

Extending to the left from flange 53 is a lug 75 through which extends the lower end of a rod 76 which extends upwardly and has the upper end thereof screw threaded into the floor 37. A nut 77 at the upper end of the rod and a pair of nuts 78 at the bottom end thereof, one above and the other below lug 75, serve to hold the rod 76 to the lug 75 and floor 37, thereby supporting the latter with respect to the chute 23. Lug 75 has a clear hole 79 through which the rod 76 is passed upwardly preparatory to threading into floor 37.

In operation, the boxes will be in the high position shown in Fig. 3 at the time of weft replenishment and the low box 31 will be empty. The binder 64 is therefore in rearmost or shuttle checking position and spring 65 holds lever 62 rearwardly in the full line position of Fig. 3 with the arm 72 overhanging and either engaging or closely adjacent to the abutment 71. If under these conditions bobbin B should be transferred downwardly into shuttle S, any vibration of the boxes incident to transfer will be arrested, inasmuch as downward motion of arm 72 is resisted by abutment 71 and the bobbin chute and shuttle boxes are therefore held in proper position for transfer.

Subsequent to replenishment another shuttle will enter box 31 and push the binder 64 to the

left, see dotted lines of Fig. 3, thereby rocking lever 62 to move arm 72 rearwardly out of alignment with the abutment 71 and over opening 73. When the boxes descend the arm 72 will move 5 downwardly through the opening 73 to the position indicated in Fig. 4. Movement of the lever 62 to locking and unlocking position goes on throughout operation of the loom independently of replenishment, but the cooperation of the several parts is such that replenishment will always occur when lever 62 is in position to prevent downward motion of the shuttle boxes at the time of replenishment.

From the foregoing it will be seen that I have 15 provided a simple form of auxiliary support for the shuttle boxes comprising a lever pivoted on the bobbin chute and having one arm to be positioned by the binder of the lower box and another arm to move into and out of holding engagement with respect to the abutment 71. It will also be seen that the lever rises and falls with the shuttle boxes and is therefore always aligned with the binder 64. Furthermore, the rod 76 provides support for the floor 37 and ties 20 the latter to the bobbin chute which in turn is supported by the lever 62 when the latter is in the full line position of Fig. 3.

Having thus described my invention it will be seen that changes and modifications may be 30 made therein by those skilled in the art without departing from the spirit and scope of the invention and I do not wish to be limited to the details herein disclosed, but what I claim is:

1. In a loom having a lay provided with a pair 35 of shuttle boxes which are shifted vertically by a downwardly yieldable actuator and wherein provision is made for downward replenishment of a shuttle in the upper shuttle box while the lower shuttle box is empty and the binder of the latter is in shuttle engaging position, a bobbin chute secured to the shuttle boxes and connected to the yieldable actuator to transmit a lifting force from the latter to the boxes, a lever pivoted on said bobbin chute, and means normally to place one arm of the lever in engaging position relatively to said binder of the lower box and place another arm of the lever over a part of the lay to prevent downward movement of the bobbin chute and boxes, entry of a shuttle into said lower box moving the binder and causing the latter to rock said lever and move said other arm out of vertical alignment with said part of the lay.

2. In a loom having a lay provided with a pair 40 of shuttle boxes which are shifted vertically by a downwardly yieldable actuator and wherein provision is made for downward replenishment of a shuttle in the upper shuttle box while the lower shuttle box is empty and the shuttle binder of the latter is in shuttle engaging position, a bobbin chute secured to the shuttle boxes and connected to the yieldable actuator to transmit a lifting force from the latter to the boxes, a lever pivoted on the bobbin chute and having an arm to engage the binder of the lower box and having a second arm to overhang a part of the lay, and yieldable means tending to hold said other arm over said part of the lay to prevent downward movement of the bobbin chute with respect to the lay, entry of a shuttle into the lower box moving the binder to cause the latter to rock said lever and move said second arm out of engaging position with respect to said part of the lay.

3. In a loom having a lay provided with a pair 45 of shuttle boxes which are shifted vertically by a downwardly yieldable actuator and wherein

provision is made for downward replenishment of a shuttle in the upper shuttle box while the lower shuttle box is empty and the binder of the latter is in shuttle engaging position, a bobbin chute secured to the shuttle boxes and connected to the yieldable actuator to transmit a lifting force from the latter to the boxes, an auxiliary support for said bobbin chute mounted on the latter for movement relatively to said chute by said binder, and means tending normally to cause a part of said support to overhang a portion of the lay to prevent downward motion of the bobbin chute and boxes with respect to the lay when said binder is in shuttle engaging position, movement of a shuttle into said lower box moving the binder to cause the latter to move the auxiliary support with respect to the bobbin chute to move said part out of vertical alignment with said portion of the lay.

4. In a loom having a lay provided with a pair of shuttle boxes which are shifted vertically by a downwardly yieldable actuator and wherein provision is made for downward replenishment of a shuttle in the upper shuttle box while the lower shuttle box is empty and the binder of the latter is in shuttle engaging position, a bobbin chute secured to the shuttle boxes and connected to the yieldable actuator to transmit a lifting force from the latter to the boxes, an auxiliary support for said bobbin chute mounted on the latter for horizontal movement relatively thereto by said binder but prevented from moving bodily downwardly with respect to said chute, and means normally causing said support to overhang a portion of the lay when the binder is in shuttle engaging position, said support being moved out of vertical alignment with said portion of the lay by said binder when the latter is moved by a shuttle entering the lower box.

5. In a loom having a lay provided with a pair of shuttle boxes which are shifted vertically by a downwardly yieldable actuator and wherein provision is made for downward replenishment of a shuttle in the upper shuttle box while the lower shuttle box is empty and the binder of the latter is in shuttle engaging position, a bobbin chute secured to the shuttle boxes and connected to the yieldable actuator to transmit a lifting force from the latter to the boxes, a stud secured to said chute and extending horizontally under said shuttle boxes, and a lever pivotally mounted on said stud for movement in a vertical plane transverse of said binder, a spring tending normally to hold said lever with one part thereof in engaging position relatively to the binder and another part thereof over a portion of the lay, said binder when moved by a shuttle entering the lower box engaging and rocking said lever against the action of said spring to move said other part of

the lever out of vertical alignment with said portion of the lay.

6. In a loom having a lay, shiftable shuttle boxes on the lay, a shuttle binder for one of said boxes, a downwardly yieldable actuator to shift said shuttle boxes vertically with respect to the lay, a bobbin chute connected to the actuator and the shuttle boxes to transmit an operating force from said actuator to the shuttle boxes, a lock pivotally mounted on said bobbin chute, and means normally holding said lock in locking position to engage the lay and prevent downward movement of the boxes and chute with respect to the lay, said lock positioned for movement by said binder to non-locking position with respect to the lay.

7. In a loom having a lay provided with a pair of shuttle boxes which are shifted vertically by a downwardly yieldable actuator and wherein provision is made for downward replenishment of a shuttle in the upper shuttle box while the lower shuttle box is empty and the binder of the latter is in the path of a shuttle entering the lower box, a bobbin chute secured to the shuttle boxes and connected to the yieldable actuator to transmit a lifting force from the latter to the boxes, a lock movably mounted on the bobbin chute into and out of locking relation with respect to the lay, and means to move said lock into locking position when the binder is in said shuttle path, said lock being moved out of locking position by the binder when the latter is moved by a shuttle entering the lower box.

8. In a bobbin chute for a shuttle box on a loom lay having a shuttle binder normally in the path of a shuttle entering the shuttle box, means by which said chute can be secured to said shuttle box, a stop lever pivoted on said chute, and a spring supported by said chute and connected to said lever and tending to hold one part of said lever in position to overhang a portion of the lay to prevent movement of the chute in one direction on the lay and urge another part of the lever toward said binder, said other part being movable by said binder to move said one part out of overhanging position relatively to said portion of the lay.

9. A bobbin chute and shuttle box assembly for a loom lay, said assembly comprising a depleted bobbin guide secured to a shuttle box having a shuttle binder, a lock mounted on and movable with respect to the guide, and means forming part of the assembly acting normally to hold a part of the lock in position to overhang a portion of the lay, said lock having another part movable by the binder to move the first part out of overhanging position with respect to said portion of the lay.

BENJAMIN W. BROUWER.
